United States Patent Office

Des. 175,485
Patented Aug. 30, 1955

175,485

ONE PIECE TIE DOWN DEVICE OR SIMILAR ARTICLE

Harry Weiss, Bayside, N. Y.

Application March 28, 1955, Serial No. 35,246

Term of patent 7 years

(Cl. D54—11)

FIG. 2

FIG. 1

FIG. 3

Fig. 1 is a side elevational view on a one piece tie down device, embodying my new design;

Fig. 2 is a top plan view thereof; and

Fig. 3 is a front end view thereof.

I claim:

The ornamental design for a one piece tie down device or similar article, as shown.
